NOVELTY CIGAR CONTAINER OR THE LIKE

Howard L. Epperson, Sweetwater, and Matthew J. Nesbit and Robert F. Myrick, Jr., Concord, Tenn.

Application May 18, 1955, Serial No. 36,081

Term of patent 14 years

The broken line disclosure of the cigar is for illustration only.

We claim:

The ornamental design for a novelty cigar container or the like, substantially as shown and described.
